UNITED STATES PATENT OFFICE

138,381

DESIGN FOR A FISHING FLY BODY

Kenneth D. Richards, Gardner, Mass.

Application February 18, 1944, Serial No. 112,629

Term of patent 3½ years

(Cl. D31—4)

To all whom it may concern:

Be it known that I, Kenneth D. Richards, a citizen of the United States, residing at Gardner, in the county of Worcester and Commonwealth of Massachusetts, have invented a new, original, and ornamental Design for a Fishing Fly Body, of which the following is a specification, reference being had to the accompanying drawing, forming part thereof.

Fig. 1 is a plan view of a fishing fly body showing my new design;

Fig. 2 is a perspective view;
Fig. 3 is an end elevational view; and
Fig. 4 is a transverse sectional view taken on the line 4—4 of Fig. 1.

I claim:
The ornamental design for a fishing fly body, as shown.

KENNETH D. RICHARDS.
